UNITED STATES PATENT OFFICE

ELI T. STARR, OF PHILADELPHIA, PENNSYLVANIA, ASSIGNOR TO SAMUEL S. WHITE, OF SAME PLACE.

IMPROVEMENT IN HEAD-RESTS FOR DENTAL CHAIRS.

Specification forming part of Letters Patent No. 171,539, dated December 28, 1875; application filed November 5, 1875.

CASE B.

To all whom it may concern:

Be it known that I, ELI T. STARR, of Philadelphia, Pennsylvania, have invented certain new and useful Improvements in Head-Rests for Dentists' and other Chairs, of which the following is a specification:

My invention relates to head-rests of that class capable of adjustment vertically, laterally, and longitudinally relatively to the chair. Its object is to give even a wider range of adjustment to the head-rest than has heretofore been practicable, which end I attain by securing the supporting-bar on one side of the central line of the head-rest and mounting it in a turning-post, in which it freely slides and turns when released from its clamp-screw, whereby the position of the head-rest may be reversed.

The subject-matter claimed is hereinafter specified.

In the accompanying drawings, Figure 1 represents a view, in perspective, of my improved apparatus with the head-rest elevated; and Fig. 2, a vertical longitudinal central section therethrough, on an enlarged scale, showing the head-rest as depressed. The head-rest A, of approved construction, has secured to it on one side of its central longitudinal line, by means of suitable brackets b b', a rod, B, capable of moving freely endwise and of turning in its socket or bearing in a sectional adjusting frame or holder, C C', in turn capable of turning and sliding upon the usual supporting-bar E, vertically adjustable upon the back of the chair by well-known means. This adjusting-frame is held by the usual clamp-screw D.

I will now proceed to describe the distinguishing characteristic of my invention. The lower portion, C', of the holder is provided with a bearing-shoe, c, acted upon by the clamp-screw, and, in turn, bearing upon the supporting-bar E. Another shoe, c', rests upon the upper side of the support E and extends into the upper section C far enough to bear against another shoe, c'', upon which the

supporting-rod B rests. The upper section, C, of the adjusting-frame, which I call a turning-post, is secured to the lower one by means of an annular flange, F, screwing upon the lower section and overlapping a shoulder on the turning-post, said ring being held in place by a check-screw, f.

By this mode of construction the turning-post is capable of turning freely in the lower portion, C', of the adjusting-frame, which gives the capacity of varying the angle of the head-rest horizontally relatively to the chair, even to the extent of reversing it entirely, and by then swinging the head-rest over by rocking it in its bearings it may be adjusted vertically to any desired position. It may also be moved laterally by sliding it endwise in the turning-post, and the latter may be adjusted backward or forward, or at any desired angle, by sliding or turning the adjusting-frame on its supporting-bar, and all the parts may be firmly clamped in any desired position by tightening the single clamp-screw.

The operation of my invention and its advantages will readily be understood from the foregoing description.

I claim as my invention—

1. A head-rest mounted upon a supporting-bar, secured upon one side of its longitudinal center and rocking in a turning-post, whereby the head-rest is rendered reversible and a wide range of motion imparted to it, substantially as set forth.

2. The sectional adjusting-frame hereinbefore described, consisting of a lower section, a turning-post mounted thereon, and a clamp-screw, these members being constructed and operating in combination, substantially as hereinbefore set forth.

In testimony whereof I have hereunto subscribed my name.

ELI T. STARR.
